UNITED STATES PATENT OFFICE.

HERBERT LEGGETT, OF KANSAS CITY, MISSOURI.

SPARK PLUG.

Application filed May 28, 1923. Serial No. 641,916.

To all whom it may concern:

Be it known that I, HERBERT LEGGETT, a citizen of the United States, residing at Kansas City, in the county of Jackson and 5 State of Missouri, have invented certain new and useful Improvements in Spark Plugs, of which the following is a specification.

My invention relates to spark plugs of the 10 character employed in the ignition systems of internal combustion engines, and my primary object is to provide a durable device of this character which will not readily become fouled with oil and the products of 15 combustion, but on the contrary, will be practically self-cleaning and require but little attention after being installed in an engine.

I attain the foregoing object by employing, among other features, a new form of electrode which is so shaped as to direct a stream of gases around the companion electrode with such velocity that oil and the products of combustion cannot readily 25 lodge between said electrodes and cause a short-circuit of the ignition current.

Said new form of electrode is preferably 30 constructed of metal, such, for example, as nichrome, or Monel metal, which is capable of successfully withstanding high temperatures, and is purposely made thin so that it will readily become heated with each 35 explosion to a sufficient degree to burn off oil deposits, and yet not retain enough heat to preignite the successive combustible charges.

Said new form of electrode also coacts 40 with the shell of the spark plug in forming a trap for intercepting a portion of the oil and products of combustion before they can enter the spark plug far enough to cause ignition trouble.

In order that the invention may be fully 45 understood, reference will now be had to the accompanying drawing, in which:

Fig. 1 is a side elevation of the spark plug.

Fig. 2 is a vertical section on line II—II of Fig. 1.

Fig. 3 is a detail perspective view of a 50 tubular electrode constituting an important feature of the invention.

Fig. 4 is a detail perspective view of an 55 annular spacing element employed in carrying out the invention.

Referring now to the various parts, 1

designates a metallic shell having external threads 2 at its lower end so that it may be screwed into the cylinder head of the engine, not shown.

3 designates an insulator made of any suitable material such as porcelain, mica, etc. Said insulator may be secured within the shell 1 in any preferred or well-known manner. In the drawing, I have shown it 60 removably held in position by a bushing 4 threaded into the upper portion of the shell 1, an asbestos or other suitable gasket 5 being placed about such insulator 3 to protect the same from being damaged when the bushing 4 is screwed into the shell 1, and from expansion strains.

A stem-like electrode 6, extends through the insulator 3 and is provided at its upper threaded end with the usual nuts 7 and 8 adapted to hold the terminal of a high tension lead wire of the usual ignition system, not shown. The lower portion of the electrode 6 extends axially through a tubular electrode 9 preferably shaped somewhat on 70 the order of a Venturi tube. The upper enlarged end of the tubular electrode 9 is provided with a marginal flange 10, which is grounded on an annular shoulder 11 within the shell 1 by an annular spacing element 80 12 which is pressed downwardly upon the flange 10 by the insulator 3 and the interposed gasket 5. The interior surface of the lower constricted portion 13 of the tubular electrode 9 is spaced from the insulated electrode 6 to leave an annular spark gap 14.

By constructing the tubular electrode 9 as shown and described, it is apparent that when the combustible mixture is compressed in the combustion chamber of the engine a 95 portion will be forced into the chamber 15, formed by the tubular electrode 9, the spacing element 12, and the lower portion of the insulator 3. Then, as such portion of the combustible mixture is exploded by the 100 spark at the gap 14, the resultant high pressure will cause the burnt gases to rush out through the restricted opening 13 of the tubular electrode 9 at such high velocity as to carry off carbon and other products of 105 combustion which would otherwise tend to cause a short circuit between the electrodes 6 and 9. It is also apparent that any products of combustion blown from the combustion chamber of the engine into the lower portion of the spark plug will be trapped in the chamber 16, formed by the lower interior 110

portion of the shell 1 and the exterior portion of the tubular electrode 9, and thus be prevented from collecting around the lower portion of the insulator 3 and causing a short circuit between the electrode 6 and the shell 1.

Oil is also prevented from becoming deposited in the restricted opening 13 of the tubular electrode 9 by the stream of gases 10 rushing through said opening, and further, by the relatively high temperature attained by the tubular electrode 9 due to the heat generated by the explosion of the successive charges of the combustible mixture.

15 From the foregoing description it is apparent that I have produced a spark plug embodying the advantages above pointed out, and while I have shown and described the preferred construction, combination and

arrangement of parts, I reserve the right to 20 make such changes as properly fall within the spirit and scope of the claim.

Having thus described my invention, what I claim and desire to secure by Letters Patent, is:

25

In a spark plug, an outer shell, a stem-like electrode extending through and insulated from said shell, and a second electrode cooperatively associated with said first electrode, pendent from interior of outer shell, 30 and consisting of two thin conical tubes joined at their reduced ends.

In testimony whereof I affix my signature, in the presence of two witnesses.

HERBERT LEGGETT.
